MILLING AND PARALLELING MACHINE

Emmet E. Welch, Topeka, Kans.

Application August 18, 1937, Serial No. 159,676

1 Claim. (Cl. 90—21)

My invention relates to a milling and paralleling machine.

The object of my invention is to provide a milling and paralleling machine, primarily for use in the preparation of dental bridges, comprising a rotating bit mounted above a seat arranged for movement in a plane normal to the axis of the bit.

A further object of my invention is to provide a machine of the kind described in which the movement of the seat can be accomplished in two directions precisely at ninety degrees.

These and other objects will hereinafter be more fully explained. Referring to the drawings in which like characters apply to like parts in the different views:

Figure 1 is an elevation of the machine showing an adjustable base carrying a casting, positioned in the seat.

Figure 2 is a plan view of Figure 1 with the tool post shown in section.

Figure 3 is a fragmentary plan view showing the bit mechanism and adjustments.

Figure 4 is an enlarged section taken on the line 4—4 in Figure 2.

Figure 5 is a fragmentary view of one end of the carriage showing the driving and locking means.

Figure 6 is an enlarged plan view of the seat.

Figure 7 is an enlarged view of the chuck and bit with respect to the work.

The machine described has a bed plate 1, upon which are mounted a tool post 2 and four rail posts 3, 4, 5 and 6 respectively. A guide rail 7, is supported between the posts 3 and 4 and a similar guide rail 8 is supported between the posts 5 and 6. The rail 8 is parallel to the rail 7. A rack 7' is affixed to the rail 7 and similarly a rack 8' is affixed to the rail 8 in such a manner as to allow the teeth of the racks to extend below the lower surfaces of the respective rails. The carriage 9 is slideably mounted on the rails 7 and 8 as shown at A and B. The guide rails 10 and 11 are supported in the ends of the carriage and are parallel to each other. The rails 10 and 11 are positioned in a direction 90 degrees to the rails 7 and 8. The plane of the rails 10 and 11 is parallel to that of the rails 7 and 8. The shaft 12, trunnioned in the bearings 13 and 14 at each end of the carriage 9 has a driving wheel at one end and adjacent thereto a locking wheel 16 which engages the threaded portion of the shaft 12 at C. A pinion gear 17 is mounted on the shaft 12 and engages the rack 8'. A similar gear 18 engages the rack 7'. Rotation of the driving wheel 15 moves the carriage on the rails 7 and 8. A clock-

wise rotation of the locking wheel 16 until it is in firm contact with the bearing 13 provides a brake to set the carriage 9 against movement.

The seat 19 is slideably mounted on the rails 10 and 11. The shaft 20 is carried in the bearings 21 and 22 on the lower side of the seat member. A driving wheel 23 is affixed at one end of the shaft and a locking wheel 24 at the other end in threaded engagement with the shaft. The pinion 25 is firmly affixed to the shaft 20 at its mid point and engages the rack 26, set in the floor of the carriage at D. Rotation of the driving wheel 23 moves the seat along the guides 10 and 11. Clockwise rotation of the locking wheel 24 will set the seat against movement.

An arm 27 is rigidly connected to the top of the post 2 and extends therefrom to a point approximately over the center of the base 1. The free end of the arm 27 is bored at E to receive the sleeve 28. A cut at F allows the positioning of the pinion gear 29, which is mounted on the shaft 30. A slot at G extends from the cut F along the arm 27. The shaft 30 is rotatably positioned in the arm 27. The driving wheel 31 rigidly affixed to one end of the shaft 30 serves to rotate the pinion gear 29, which engages the rack 32 set in the sleeve 28 and raises or lowers the said sleeve. The locking wheel 33 is engaged on the threaded end of the shaft 34. Clockwise rotation of the locking wheel 33 will distort the arm 27 at the slot G to prevent movement of the sleeve 28. A spindle 35 is rotatably mounted in the sleeve 28. The upper extremity of the spindle has the connection 36, to which may be attached a drive, preferably the chuck of a dental drill. A chuck 37 is positioned at the lower end of the spindle and arranged to hold a bit 38.

Figure 7 illustrates the use of a side cutting or milling bit 38 as applied to the inlay at H.

The use of the machine herein described is primarily that of making precision cuts in the form of slots or grooves in dental gold inlays, three-quarter gold crowns, full gold crowns, and the like which have been previously fitted to the teeth in the mouth of a patient, and transferred to a metal die or cast of the jaw constructed from an impression of said jaw. These inlays are intended for attachments to abutment teeth to support precision removable dental bridges. The proper operation of removable bridges depends on the precision of the cuts made in the abutment inlays. These cuts must be perpendicular to the same plane and in many cases one cut may require another cut at exactly 90 degrees from the first. This machine provides the movements

necessary to prepare the required work in that the seat must remain continuously in the same plane and at times move in two definite directions at 90 degrees. The arrangement illustrated and described provides the means of movement with the conservation of height. The seat is designed preferably to accommodate an adjustable base as illustrated, however I do not confine myself to such a base specifically.

10 In operation, the base is placed in the seat with the work turned to the most convenient position. The set screws 39 are rotated to clamp the said base. The work is then positioned under the bit 38 by rotation of the wheels 15 and 23. The bit 15 is raised or lowered by the wheel 31 and then clamped in position by the locking wheel 33. If the direction of the cut is along the rails 10 and 11, the locking wheel 16 is rotated to clamp the carriage and the work is fed against the bit by 15 rotation of the wheel 23. If the direction of the cut is along the rails 7 and 8, the seat is clamped by the rotation of the wheel 24 and the work is fed against the bit by the rotation of the wheel 15.

The machine herein described provides a defi-

nite guide for the machining and milling required in the preparation of removable dental bridges and such modifications may be employed as lie within the scope of the appended claim and what I claim as new and desire to secure by Letters Patent is:

A milling and paralleling machine comprising a carriage, a base and a seat, the said carriage slideably positioned on guides, the said guides suspended above the base on posts, the said seat 10 slideably positioned on a second set of guides, the said second set of guides positioned on the carriage at right angles to and below the first set of guides, racks affixed to the first set of guides, pinions rotatably mounted on the carriage and in engagement with the rack on the first set of guides, a second rack positioned on the carriage and a pinion rotatably mounted on the seat and in engagement with the said second rack, wheels as means to drive the said pinions and other 20 wheels as means to lock the said pinions, a bit rotatably mounted on the base and vertically adjusted to the seat.

EMMET E. WELCH.
